UNITED STATES PATENT OFFICE.

HARRISON WALTER WELTY, OF FORT WAYNE, INDIANA.

FLY-ESCAPE FOR SCREENS.

1,029,330.

Specification of Letters Patent. Patented June 11, 1912.

Application filed July 14, 1911. Serial No. 638,479.

To all whom it may concern:

Be it known that I, HARRISON W. WELTY, a citizen of the United States, and a resident of Fort Wayne, in the county of Allen 5 and State of Indiana, have invented a new and Improved Fly-Escape for Screens, of which the following is a full, clear, and exact description.

The object of the invention is to provide 10 a screen for doors and windows of buildings so constructed as to permit the escape from the building of such flies and other insects as may be upon the inside and yet effectually prevent the entrance to the building of such 15 flies and insects as may be on the outside.

Reference is to be had to the accompanying 20 drawings constituting a part of this specification, in which similar characters of reference denote corresponding parts in all the views, and in which—

Figure 1 shows a perspective view of a portion of a door or window screen embodying the invention and looking at the outer side thereof; Fig. 2 shows a portion 25 of the top of a door or window screen somewhat enlarged looking at the inner side, a portion of the outer guard being broken away at the left hand end, and a portion of the frame being shown in section; and Fig. 3 shows a vertical section taken on the 30 line 3—3 in Fig. 1.

The screen comprises a frame A of the usual form, and made of any usual or preferred material. Within the frame A is secured the main panel B of the screen, constructed of the ordinary screen wire, the marginal edge b of which is received within a rabbet b' and beneath a cleat b'', all in a usual and well known manner. The 35 panel B at or near its upper edge is provided with a line of openings C whereby to permit the flies or insects to pass through the screen panel B.

In order to insure that the flies or other 40 insects will be permitted to pass through from the inside out, not from the outside in, the apparatus is provided with an inner guard D which is secured to the screen panel B by fastening devices d which pass 45 through the screen panel B and through spacing blocks d', the upper end of the blocks d' being beveled as shown at d'', and

the upper edge of the guard D being bent as shown at d³, and having its upper edge d⁴ intermeshing with the screen panel B. 55 The lower end d⁵ of the guard D is spaced away from the screen panel B so that an opening is provided for the passage of the flies or other insects upward beneath the guard D and between the guard D and the 60 screen panel B. The upper beveled end d² of the guard D covers the row of apertures C.

Upon the outer surface of the screen panel B is a guard E provided with a row 65 of openings e surrounded by eyelets e'. The guard E is fastened to the screen panel B by fastenings e² which pass through the upper edge of the guard E and through spacing blocks e³ corresponding to the spacing block d', and through the screen panel B. The lower end of the guard E is bent 70 toward the screen panel B as shown at E⁴, and its extreme lower edge has an intermeshing engagement with the screen panel 75 B below the line of perforations C. Preferably the perforations C will be displaced or staggered with relation to the perforations e.

In operation, the screen being inserted 80 in the door or window of a building, with the guard B upon the inside of the building, it will be apparent that a fly or insect climbing up the screen panel B may enter 85 between the guard D and the screen panel and pass through the opening C, thence through an opening e in the guard E and escape from the building. Because the 90 openings C and e are displaced with relation to each other, a fly or insect will not be likely to find entrance to the building from the outside.

Having thus described my invention, I claim as new and desire to secure by Letters Patent:

A fly escape for screens, comprising a screen panel having a line of openings near its upper edge, a guard extending across the inside of the screen panel near its upper edge, spaced therefrom, and open along 100 its lower edge and intermeshing with the screen panel above the line of openings therein, a guard extending across the outer side of the screen panel above the inner

guard, its lower edge intermeshing with the screen panel below the line of openings therein, a line of openings in the outer guard, and vertically disposed spacing blocks interposed between the guards and the screen panel, and means for securing the spacing blocks to the screen panel.

In testimony whereof I have signed my name to this specification in the presence of two subscribing witnesses.

HARRISON WALTER WELTY.
